The ornamental design for a visual alarm for alarm unit, as shown and described.

DESCRIPTION

FIG. 1 is a perspective view of a visual alarm for an alarm unit in accordance with the present invention;

FIG. 2 is front side view thereof;

FIG. 3 is right side view thereof;

FIG. 4 is left side view thereof;

FIG. 5 is rear side view thereof;

FIG. 6 is bottom view thereof; and,

FIG. 7 is top view thereof.

The features shown in broken lines in the various Figures are for illustrating environmental structure and form no part of the claimed design.
